Specification for Design.

Patented Nov. 8, 1910.

Application filed August 16, 1910. Serial No. 577,530. Term of patent 14 years.

To all whom it may concern:

Be it known that I, ANDREW J. SANFORD, a citizen of the United States, residing at Newark, county of Licking, and State of Ohio, have invented a new, original, and ornamental Design for Light-Shades, of which the following is a specification, reference being had to the accompanying drawing, forming a part thereof.

The figure is a perspective view of a light shade showing my new design.

The leading features of my design comprise a shade having an upper portion of

general truncated cone shape ornamented with longitudinally extending prisms, and a lower skirt portion of general truncated shape ornamented with a Grecian design or border around the same.

I claim:

The ornamental design for a light shade, as shown and described.
